CIGAR OR CIGARETTE LIGHTER

Filed April 17, 1929

Inventor:

Joseph J. LISS,
By *Blindfold Park - Carlson*
Atty's.

UNITED STATES PATENT OFFICE

JOSEPH J. LISS, OF CHICAGO, ILLINOIS

CIGAR OR CIGARETTE LIGHTER

Application filed April 17, 1929. Serial No. 355,749.

The invention relates generally to lighters and more particularly to a cigar or cigarette lighter of the flint ignition type.

Heretofore difficulty has been experienced in the use of lighters of the character indicated because of the tendency of the flint adjusting device, which is usually a screw threaded member, to be altered when carried about in the user's pocket, or as a result of careless handling of the lighter. This necessitated frequent readjustment of the flint and often resulted in loss of the adjusting device thereby rendering the lighter inoperative and useless. The provision of threaded locking nuts has been resorted to, but this alternative does not overcome the difficulty and inconvenience above mentioned.

The primary object of the invention, therefore, is to overcome the difficulties heretofore experienced by providing a lighter of the flint ignition type having a new and improved flint adjusting means which is not subject to accidental displacement or loss, and which is adapted to advance the flint with greater facility.

Another object of the invention is to provide a lighter of the above character in which the adjustment of the flint to operative contact with the friction wheel may be effected readily by turning an adjusting member with the fingers and in which the member is automatically locked after such adjustment.

Other objects and advantages of the invention will become apparent from the following detailed description taken in connection with the accompanying drawings, in which:

Figure 1 is a side elevation of a lighter embodying the features of the present invention.

Fig. 2 is a sectional view taken along line 2-2 of Fig. 1.

While the invention is susceptible of various modifications and alternative constructions, I have shown in the drawings and will herein describe in detail the preferred embodiment, but it is to be understood that I

do not thereby intend to limit the invention to the specific form disclosed, but intend to cover all modifications and alternative constructions falling within the spirit and scope of the invention as expressed in the appended claims.

Referring to the drawings, the invention in its exemplary form is embodied in a lighter of the flint ignition type having a well or body section 10 adapted to receive a suitable wick (not shown) to be saturated with a combustible and volatile liquid.

In lighters of the flint ignition type, the combustible gas rising from the liquid with which the wick is saturated is adapted to be ignited by a spark projected from a toothed wheel when that member is rotated in frictional contact with a flint. Herein a toothed wheel 11 is rotatably supported upon a pin 12 journaled at opposite ends in spaced parallel arms 13 joined at their lower ends to form a U-shaped bracket. The bracket is rigidly supported adjacent the side of the well 10 as by a short projection 14 of the base of the bracket in such manner that a spark projected tangentially from the lower edge of the wheel will be discharged through an opening 15 into the combustible gas above the wick.

A flint 16 is slidably mounted for engagement with the wheel 11 in a guideway 17 formed, in the present instance, by longitudinal grooves cut in opposed inner faces of the arms 13. The guideway 17 may be threaded substantially throughout its length and terminates in an opening in the intermediate portion of the bracket. This opening is screw threaded to receive a threaded adjusting member in the form of a headed screw 18 which may be turned to advance the flint toward the friction wheel or removed to permit insertion of a new flint.

To enclose the head of the screw which projects below the bracket, a cap in the form of a sleeve 19 is mounted on the shank of

the screw with one end recessed to receive the head of the screw. Relative rotation between the screw and the sleeve is prevented in the present instance by engagement of a squared or non-circular section of the screw shank with a non-circular opening in the upper end of the sleeve defined herein by an internal flange 20. Thus, the sleeve is adapted to slide longitudinally along the shank of the screw. By grasping the outer knurled surface of the sleeve, the sleeve and the screw may be turned to advance the flint toward the wheel 11.

Means is provided for locking the screw 18 in any desired position of adjustment and preferably such means is embodied in the members constituting the adjusting means and the flint supporting means above described. To this end the upper end of the sleeve 19 is adapted for non-rotatable or locking engagement with the end of the flint supporting bracket and such engagement is maintained automatically while the lighter is being carried about in the user's pocket. This is accomplished by forming lugs 21 on diametrically opposite sides of the sleeve beyond the flange 20 which lugs define an end notch which is adapted to receive the lower flattened end of the bracket when the sleeve is moved along the shank of the screw in either of two fixed angular positions relative to the bracket.

As means for locking the sleeve against rotation and maintaining such locking engagement, a spring 22 is coiled around the shank of the screw within the sleeve and acts in compression between the head of the screw and the flange 20 to urge the sleeve axially toward the bracket. If, in this axial movement, the notch in the sleeve registers with and receives the flattened end of the bracket, the latter will serve to hold the sleeve effectively against the normal tendency of the sleeve to turn when carried about in the user's pocket.

When readjustment of the flint becomes necessary, the user grasps the sleeve and retracts the same out of locking engagement with the bracket. Then the sleeve may be freely rotated in increments of one-half revolution to advance the flint to the desired extent. With the present locking arrangement wherein the sleeve must be turned through one or more half revolutions, the adjustment of the flint may be accurately gaged. Upon releasing the sleeve it will automatically move to locked position under the influence of the spring 22 thereby insuring a permanent adjustment which cannot be altered except by the positive action of the user. To replace the flint, the sleeve may be retracted and turned in a direction to remove the screw from the bracket whereupon a new flint may be inserted in the guideway

through the opening in the end of the bracket.

I claim as my invention:

1. In a lighter of the flint ignition type, the combination of a member carried by the lighter and rotatably supporting a wheel, said member providing a guideway for receiving a piece of flint to be engaged by said wheel, a screw threading into said member axially of said guideway, a sleeve enclosing the headed end of said screw and having a non-circular opening through which a non-circular portion of said screw projects to permit of longitudinal movement of the sleeve relative to the screw but preventing relative rotational movement therebetween, means carried by the sleeve coacting with said member to lock the sleeve against rotation when engaging said member, and a spring acting between said sleeve and said screw to urge the sleeve into locking engagement with said member but permitting retraction of the sleeve whereby the screw may be turned by rotation of the sleeve to advance the flint toward said wheel.

2. In a lighter of the flint ignition type, the combination of a member carried by the lighter and rotatably supporting a wheel, said member providing a guideway for receiving a piece of flint to be engaged by said wheel, a screw threading into said member to position said flint relative to said wheel, a sleeve enclosing said screw and arranged for longitudinal movement on and held against rotation relative to said screw, lugs on said sleeve and said member coacting to prevent relative rotation between said sleeve and the member, and means urging said sleeve into locking engagement with said member.

3. In a lighter of the flint ignition type, the combination of a rotatable friction wheel, a bracket providing a guideway for receiving a piece of flint to be engaged by said wheel, a screw threading into said bracket to position said flint relative to said wheel, a member non-rotatably but slidably enclosing the headed end of said screw, a lug on said member adapted to engage said bracket to prevent rotation of said member relative to said bracket, and a spring acting between said member and said screw to urge said member into locking engagement with said bracket.

4. In a lighter of the flint ignition type, having a friction wheel and flint, the combination of means providing a guideway for receiving a piece of flint to be engaged by said wheel, a threaded member for positioning a piece of flint in operative relation with said wheel, a sleeve enclosing said threaded member and held against rotation relative thereto, and means on said sleeve providing for a locking engagement between said sleeve and said guide means.

5. In a lighter of the flint ignition type,

the combination of a friction wheel and means providing a guideway for receiving a piece of flint to be engaged by said wheel, a threaded member to advance said flint into engagement with said wheel, a sleeve mounted for movement longitudinally of said threaded member and held against rotation relative thereto, means on said sleeve providing for non-rotative engagement between said sleeve and said lighter, and spring means acting to normally urge said sleeve into locked position.

In testimony whereof, I have hereunto affixed my signature.

15 JOSEPH J. LISS.
